UNITED STATES PATENT OFFICE.

ALFRED B. FOWLER, OF BEVERLY, MASSACHUSETTS, ASSIGNOR TO UNITED SHOE MACHINERY CORPORATION, OF PATERSON, NEW JERSEY, A CORPORATION OF NEW JERSEY.

HEEL-SHAPING MACHINE.

Application filed September 24, 1924. Serial No. 739,615.

This invention relates to machines for shaping heels and more particularly to machines for trimming the periphery as distinguished from the breast of a heel. In some respects the invention is more particularly concerned with machines in which a profile of predetermined curvature is imparted to the periphery of the heel by a cutter having that profile.

In nearly all, if not quite all, cases a heel that has a curved profile also has a wedge factor, the latter consisting in a pitch or inclination of the base surface relatively to the tread surface, in consequence of which the heel has greater height at the back than at the breast. It may therefore be stated as a general rule that a curved profile is accompanied by a wedge factor, and exceptions to this rule, if any, may be disregarded for purposes of discussing the present invention. Louis heels, Cuban heels and military heels are common examples of heels having curved profiles and more or less of a wedge factor. In shaping the peripheries of such heels it has heretofore been the practice to do it by two successive trimming operations, by the first of which the body of the heel is shaped and by the second of which the wedge-shaped portion is trimmed. Heretofore no machine capable of shaping the entire periphery in one operation in such a way as to compensate for the wedge factor and at the same time produce a heel of the desired shape has gone into general use.

It has been proposed to solve this problem by equipping a heel-trimming machine with a movable toplift guard as well as a movable rand-crease guard, and to provide means operable by the operative to shift said guards lengthwise of the profile of the cutter while the latter is operating upon a heel. This proposed construction forms the subject-matter of Letters Patent of the United States No. 1,513,804, granted November 4, 1924, upon an application of Frank A. Eich, and in that case the problem of covering and uncovering a portion of the trimming cutter to compensate for the graduated height of the heel, caused by the wedge formation, is solved by mechanism operable manually and independently to shift the toplift guard as the shaping operation progresses.

In view of the above-mentioned problems

and conditions, an object of the present invention is to provide an improved heel-shaping machine by which a heel having a wedge factor may be shaped with a curved profile in a single operation without dependence upon skill, judgment or special effort on the part of the operative to compensate for the wedge factor.

A feature of the invention consists in a heel-shaping machine having a movable toplift guard and means operable by the shoe for shifting said guard heightwise of the heel to various positions.

When a cutter having a curved profile is used to shape the entire height of a wedge heel in one operation it is necessary, if the curve is not uniform, to change the relative positions of the cutter and the toplift guard as the trimming progresses around the heel, so that the guard will cover and uncover certain portions of the cutter according to the particular point of the heel on which it is operating. This necessity is most marked in the case of a Louis heel, since, if the sharply curved portion of the cutter that is used to shape the back of the heel is used also in its entirety to trim the sides, it will cut so deeply as to strike the heel nails and to make the heel too narrow in the waist. Consequently, the above-mentioned feature of the present invention is preferably embodied in mechanism operable by the turning of the shoe to shift the toplift guard as aforesaid so that it will cover a portion of the cutter when either side of the heel is presented to the cutter and will uncover that portion gradually and progressively as the trimming progresses along one side of the heel from the breast to the back. Conversely, the shifting mechanism is also preferably constructed to cause the guard to cover that portion of the cutter gradually and progressively as the trimming progresses along the opposite side of the heel from the back toward the breast.

In another aspect, the invention consists in an organization comprising two movable heel-engaging members, for example, a toplift guard and a heel-rest, and mechanism operable by the shoe to shift said members relatively to each other according to their individual requirements.

Another feature of the invention consists in the provision, in an organization such

as that above indicated, of a spring-stressed rand-crease guard normally urged toward the toplift guard and adapted to yield in the opposite direction according to variations in position of the toplift guard and in response to the demands of the wedge factor of the heel. Thus, in operation, the heel is positioned heightwise, that is, lengthwise of its axis of turning, by its own turning movement about such axis, through the agency of a movable toplift guard, while the rand-crease guard automatically follows the pitch and shifting of the rand-crease.

To utilize the turning movement of the shoe for the purpose of shifting the heel-positioning member as aforesaid, the invention provides a follower formed to embrace the shoe and arranged to swing about an axis substantially parallel to the height or axis 20 of the heel, and means operable by said follower to produce the desired shifting movement of said heel-positioning member.

Another object of the invention is to provide, in a heel-shaping machine, a movable heel-rest and mechanism operable by the shoe for shifting it as successive points along the periphery of a heel are presented to the cutter. In heel-shaping machines it is customary to provide a heel-rest arranged to engage the periphery of the heel to sustain the latter against the cutting stress of the cutter. By reason of the irregular contour of a heel the turning movement produces a bodily movement relatively to the heel-rest, and this relative bodily movement, when the heel-rest is stationary, as in prior constructions, shifts the theoretical tangent between the cutter and the heel. I have found that it is desirable to maintain this tangent at a fixed point, or nearly so, to keep the working conditions more nearly constant.

Accordingly another feature of the invention consists in a movable heel-rest arranged to sustain the heel against the cutting stress of the cutter, and means, preferably operable by turning the shoe, for shifting the heel-rest to maintain the tangent of the cutter and heel at a fixed point or as nearly so as the irregular contour of the heel will permit. According to this feature the movement of the heel-rest compensates for the irregular contour of the heel.

Another object of the invention is to provide for maintaining the point of contact between the heel-rest and the heel in one plane with regard to the height of the heel, that is, at a constant distance from the plane of the tread surface, notwithstanding the heightwise movement imparted to the heel by the toplift guard.

Accordingly another feature consists in an organization in which the heel-rest partakes of the shifting movement imparted to the toplift guard in addition to the aforesaid movement imparted to the heel-rest exclu-

sively. Thus, while the turning of the shoe imparts a simple shifting movement to the toplift guard it also imparts a compound shifting movement to the heel-rest.

Other features of the invention are hereinafter described and claimed and are illustrated by the drawings.

Referring to the drawings,

Fig. 1 is a front elevation of the upper portion of a heel-shaping machine constructed in accordance with this invention;

Fig. 2 is a vertical section through the structure intersected by line II-II of Fig. 1;

Fig. 3 is a perspective view including the rotary cutter-head, the guards and the heel-rest, and mechanism operable by the shoe for shifting one of the guards and the heel-rest;

Fig. 4 is a horizontal section through the structure intersected by line IV-IV of Fig. 2;

Fig. 5 is a top plan view of the assemblage shown in Fig. 4 with the addition of portions of the cutter-head, heel-rest and other parts;

Fig. 6 is a front elevation showing a heel in three successive positions and the heel-rest in three corresponding positions; and

Fig. 7 represents the cutter-head conventionally in end elevation and includes the heel-rest and the outline of that portion of the heel that contacts with the heel-rest in three successive positions corresponding to those represented in Fig. 6.

The framework of the machine, so far as it is illustrated in Fig. 1, comprises bearings 10 and 12 in which a shaft 14 is journaled. This shaft carries a cutter-head comprising two cutting blades 16, 16. The cutting edges of the blades have a profile designed to impart the desired shape or style to the heel 18 which, in the present instance, is a Louis heel. The shaft 14 also carries a pulley 20 on which a driving belt (not shown) is intended to run.

A toplift guard 24, a counter guard 26 and a heel-rest 28 are arranged to assist the operative in maintaining the heel in the desired relation to the cutter-head, each of said guards being effective, as usual, to control the depth of trimming. In the illustrated machine, both the toplift guard 24 and the heel-rest 28 are mounted to be shifted during the progress of the heel-shaping operation, as will be explained.

The most common mode of manipulation to shape a heel is to start at the left-hand side and progress around the back to the right-hand side by turning the heel in the direction indicated by an arrow in Fig. 7. Thus, the shoe occupies initially the position represented by broken lines in Fig. 3 and the operator turns it by grasping the fore-part with the right hand and swinging the

toe from top to bottom, meanwhile using the left hand to steady the heel part and maintain the counter and toplift against the counter guard 26 and toplift guard 24, respectively.

The elements A, B and C in Fig. 6 represent the heel in three positions which are respectively the initial position, the median position and the final position. In Fig. 7 the elements *a*, *b* and *c* represent the contour of that portion or cross-section of the heel that engages the heel-rest 28, and the three positions correspond respectively to those represented in Fig. 6. Figs. 6 and 7 also show three positions of the heel-rest 28, said positions being numbered 1, 2 and 3 respectively and corresponding to the three positions of the heel. To utilize the turning movement of the shoe to shift the heel-rest progressively as the shaping of the heel progresses, the machine is provided with a follower arranged to swing about a horizontal axis substantially parallel to the height of the heel, said follower having parallel arms 30, 30 arranged to straddle the forepart of the shoe, as shown in Fig. 3. The swinging movement of this follower is utilized also to shift the toplift guard 24 to various positions, as hereinafter explained.

The follower comprises, in addition to the arms 30, 30, a block 32 and an arm 34. The two arms 30, 30 extend through a hole in the block 32 and are fastened by a set-screw 36. Those portions of the arms that extend through the block are semi-circular in cross-section and each is a counterpart of the other, which formation enables a single set-screw to bind both arms and at the same time provides for adjusting the arms toward and from each other according to the width of the shoe to be straddled. The block is also bored for the reception of a cylindric portion of the arm 34 and is provided with a set-screw 38 by which it may be fastened at various positions with regard to the length of the shoe.

The arm 34 is fixed to a horizontal shaft 40 (Fig. 4) which is journaled in a fixture 42 fastened to or forming a part of the main frame of the machine. A wrist-pin 44 having a spherical head is carried by the hub of the arm 34 and is connected to an arm 46 (Fig. 1) by a connecting link 48. The connection between the link 48 and the arm 46 is a ball-and-socket connection 45 similar to that between the link and the arm 34. The arm 46 is rigidly connected to a spur gear segment 50 by a horizontal shaft 52 (see Fig. 2), said shaft being journaled in a boss 54 on the under side of a movable structure 56. The segment 50 meshes with a segment 58 formed on an arm 60, said arm being carried by the movable structure 56 and connected thereto by a pivot 62. The

arm 60 carries the heel-rest 28. The motions of the parts in this train of mechanism are as follows: The follower 30, 30 swings about the axis of the horizontal shaft 40, and the wrist-pin 44, being eccentric to said axis, is carried bodily about the latter. Thus, the wrist-pin moves the link 48 up and down to rock the arm 46 and the horizontal rock-shaft 52 to which said arm is fixed. The gear segment 50, being fixed to this rock-shaft, also partakes of this rocking movement and imparts a corresponding rocking movement to the arm 60 which rocks on the horizontal pivot 62 and carries the heel-rest 28 up and down. The train of connections just described is such that by swinging the follower comprising the arms 30, 30 to its upper position, as shown by Fig. 3, the heel-rest 28 is moved to its lowest position indicated by the numeral 1 in Figs. 6 and 7, and by swinging the follower to its lowest position shown in Fig. 1, the heel-rest is shifted to its highest position, indicated at 3 in Figs. 6 and 7. The intermediate position of the heel-rest, indicated at 2 in Figs. 6 and 7, corresponds to the median position of the follower.

As shown by Fig. 4, a cam 64 is pinned to the arm 34. The function of this cam is to shift the toplift guard and the heel-rest 95 horizontally, and the motion produced thereby causes the toplift guard to cover and uncover certain portions of the trimming blades 16, 16 during the heel-shaping operation. The cam 64 acts upon a roll 66 mounted in a carriage 68. This carriage is arranged to slide on the fixture 42 and has flange-and-groove connection therewith, as shown in Fig. 2. A compression spring 70 is arranged to maintain the roll 66 against the cam 64 and to shift the carriage from left to right under control of the cam. The left-hand end of the spring 70 is seated against a portion of the fixture 42 while the right-hand end is seated against an abutment 72 carried by the carriage 68. The toplift guard 24 is affixed to the movable structure 56 and the latter is pivotally connected to the carriage 68 by trunnions 74. By means of these connections the cam 64 operates to shift the toplift guard and the heel-rest horizontally, but the lines of motion are capable of being regulated, by means about to be described, to conform approximately to the profile of the cutters 16, 16, or at least to that portion of the profile with which the shifting movement of the toplift guard is coextensive.

As shown by Fig. 2, a stud 76 is fastened to the fixture 42 and projects upwardly through a slot in the carriage 68 and into a slot 78 formed in a bushing 80. This bushing is arranged in a socket formed in the movable structure 56 and is adapted to turn about a vertical axis for purposes of regulation. A set-screw 82 extends through a

slot 84 in the bushing and screws into the element 56, so that when it is set down tightly its head binds the bushing against rotation. The slot 78 (Fig. 5) formed in the lower part of the bushing extends diametrically thereof but by adjusting the bushing about its axis the direction of the slot 78 may be altered within the range afforded by the slot 84. As shown by Figs. 1, 3 and 5, the toplift guard 24 covers a portion of the cutter, and the profile of the portion so covered is inclined relatively to the axis of the cutter shaft. Accordingly, the bushing 80 is adjusted to place the slot 78 at an angle corresponding to the inclination of that portion of the cutter under consideration. In other words, the slot 78 is nearly, if not quite, parallel to that portion of the profile of the cutter which is within the range of travel of the toplift guard, so that as the toplift guard is shifted from right to left by the cam 64 and from left to right by the spring 70, its lines of motion will parallel the profile of the cutter.

Whenever cutting blades of a different profile are substituted, a corresponding adjustment of the lines of movement of the toplift guard may be quickly effected by loosening the screw 82 and turning the bushing 80.

The counter guard 26 is formed with a lip 86 to run in the rand-crease of the shoe and is mounted to be positioned by the shoe so that the lip 86 may take whatever position is necessary to follow the rise and fall of the rand-crease as in the case of a shoe whose heel-seat is pitched or inclined relatively to the tread surface. As shown by Figs. 1 and 3, the counter guard is carried by a member having a stem 88, and said stem is arranged to slide in a fixture 90. A screw 92 is carried by the stem 88 and projects through a slot 94 in the fixture to prevent the counter guard from turning about the axis of the stem. A compression spring 96 nested in the fixture 90 bears against the inner end of the sleeve 88 to press the counter guard toward the toplift guard but permits the counter guard to move from right to left in accordance with the demands of the rand-crease.

In using the apparatus hereinbefore described the operative places the forepart of the shoe between the parallel arms 30, 30 and places the periphery of the untrimmed heel upon the rest 28 and the periphery of the toplift against a narrow lip 98 formed on the toplift guard to control the depth of trimming. Incidentally to thus manipulating the shoe preparatory to shaping the heel, he also catches the lip 86 of the counter guard in the rand-crease and swings the toe of the shoe to its upper position as shown by Fig. 3. When the parts are in this position the heel-rest 28 is in its lowest position and

the toplift guard is advanced to the left as far as it will go, thus covering that portion of the cutter that is to be uncovered gradually until the shaping has progressed to the extreme back of the heel. The left-hand side of the heel is now presented to the cutter so that the shaping will begin at the front or breast.

The manipulation of the shoe is substantially the same as that heretofore practised. If the arms 30, 30 have been adjusted to straddle the shoe at the ball portion the toe end of the shoe will project beyond them far enough to be grasped by the right hand of the operative. While using his left hand to grasp the heel part of the shoe, the operative swings the toe toward him and downwardly, and at the same time tilts the shoe as may be necessary to maintain the counter and toplift against their respective guards. The parallel relation of the arms 30, 30 provides for tilting the shoe in the manner just mentioned.

While the shoe turns about the axis of the heel from its initial position to its median position (see B, Fig. 6, and b, Fig. 7) the toplift guard moves from the left-hand limit of its range of travel to the right-hand limit, thereby uncovering the maximum portion of the cutter to trim the back of the heel, but as the toe of the shoe swings from its median position to its final or lowest position, the toplift guard is shifted in the opposite direction, that is, from right to left. In other words, the first position and the final position of the toplift guard are identical while in its median position it is at the other end of its range of shifting movement. The work-rest 28, on the other hand, continues to move upwardly through the entire shaping operation to maintain the working point as nearly as possible at a constant level. This may be understood by reference to Figs. 6 and 7, in which position 1 of the heel-rest is its initial position, position 2 corresponds to the stage when the point of trimming has progressed to the back of the heel, while position 3 is the final position.

It is to be observed that the heel-rest 28 also partakes of the horizontal motion imparted to the toplift guard by the cam 64 and is thus maintained substantially in constant relation to the toplift guard so far as horizontal motion is concerned. Since the heel-rest partakes of the horizontal motion of the toplift guard while it receives a vertical movement, its motion may be defined as compound, while that of the toplift guard is simple. Furthermore, since the heel-rest and the toplift guard are both carried by the element 56, the horizontal component of movement of the heel-rest will partake of the regulation afforded to the toplift guard by adjusting the bushing 80.

Having thus described my invention, what

I claim as new and desire to secure by Letters Patent of the United States is:

- 5 1. A heel-shaping machine comprising a cutter for trimming the periphery of an attached heel, a movable member for engaging a shoe to position it relatively to said cutter, and means operable by the shoe for shifting said member heightwise of the heel.
- 10 2. A heel-shaping machine comprising a cutter for trimming the periphery of an attached heel, a movable toplift guard, and means operable by the shoe for shifting said guard heightwise of the heel.
- 15 3. A heel-shaping machine comprising a cutter for trimming the periphery of an attached heel, a movable guard for controlling the depth of trimming, and means operable by turning the shoe about the axis of the heel for shifting said guard to various positions.
- 20 4. A heel-shaping machine comprising a cutter for trimming the periphery of an attached heel, a movable toplift guard, and means operable by turning the shoe about the axis of the heel for shifting said guard heightwise of the heel.
- 25 5. A heel-shaping machine comprising a cutter for trimming the periphery of an attached heel, a movable toplift guard, a follower formed to embrace the shoe and arranged to swing about an axis substantially parallel to the height of the heel, and means operable by movement of said follower in one direction to shift said toplift guard in two directions successively.
- 30 6. A heel-shaping machine comprising a cutter for trimming the periphery of an attached heel, a movable toplift guard, a follower arranged to swing about an axis substantially parallel to the height of the heel and having arms arranged to straddle the shoe, and means operable by said follower to shift said guard.
- 35 7. A heel-shaping machine comprising a cutter for trimming the periphery of an attached heel, a movable toplift guard, a follower arranged to swing about an axis substantially parallel to the height of the heel and having arms arranged to straddle the shoe, and means operable by said follower to shift said guard, said arms being adjustable toward and from each other according to various widths of the shoes to be straddled thereby.
- 40 8. A heel-shaping machine comprising a cutter having a curved profile for trimming the periphery of an attached heel, a member arranged to engage the heel to control the depth of trimming, and mechanism operable by the shoe to shift said member relatively to said cutter along lines substantially parallel to said profile.
- 45 9. A heel-shaping machine comprising a cutter for trimming the periphery of an attached heel, a member arranged to engage

the heel to position it relatively to the cutter, mechanism operable by the shoe to move said member, and adjustable means for altering the direction of the lines of movement of said member.

70 10. A heel-shaping machine comprising a rotary cutter for trimming the periphery of an attached heel, a toplift guard, mechanism operable by the shoe to move said guard relatively to the cutter, and adjustable means for regulating the lines of movement of said guard to parallel the profile of said cutter.

75 11. A heel-shaping machine comprising a cutter for trimming the periphery of an attached heel, a plurality of members arranged to engage the heel to position it relatively to said cutter, and mechanism operable by the shoe to move said members relatively to each other.

80 12. A heel-shaping machine comprising a cutter for trimming the periphery of an attached heel, a plurality of members arranged to engage the heel to position it relatively to said cutter, and mechanism operable by the shoe to move said members along lines 90 angularly related to each other.

85 13. A heel-shaping machine comprising a cutter for trimming the periphery of an attached heel, a plurality of members arranged to engage the heel to position it relatively to said cutter, and mechanism operable by the shoe to move said members synchronously but in relatively different directions.

90 14. A heel-shaping machine comprising a cutter for trimming the periphery of an attached heel, a plurality of members arranged to engage the heel to position it relatively to said cutter, mechanism operable by the shoe to move said members relatively to each other, and adjustable means for altering the 100 lines of movement of one of said members individually.

105 15. A heel-shaping machine comprising a cutter for trimming the periphery of an attached heel, a member arranged to engage 110 the periphery of the heel, a member arranged to engage the tread of the heel, and mechanism operable by the shoe to move said members along non-parallel lines.

110 16. A heel-shaping machine comprising a cutter arranged to cut downwardly to trim the periphery of an attached heel, a heel-rest arranged to sustain the heel against the cutting stress, a toplift guard, and mechanism operable by the shoe to shift said heel-rest 115 up and down and to shift said toplift guard horizontally.

120 17. A heel-shaping machine comprising a cutter for trimming the periphery of an attached heel, a heel-rest arranged to sustain 125 the heel against the cutting stress of said cutter, and mechanism operable by turning movement of the shoe to shift the shoe and said heel-rest heightwise of the heel.

130 18. A heel-shaping machine comprising a

- 6
1. A cutter arranged to cut downwardly to trim the periphery of an attached heel, a heel-rest arranged to sustain the heel against the cutting stress of said cutter, and mechanism operable by the shoe to shift said heel-rest widthwise and heightwise of the heel.
2. A heel-shaping machine comprising a cutter for trimming the periphery of an attached heel, a member arranged to engage the heel to position it relatively to the cutter, a follower arranged to swing about an axis substantially parallel to the height of the heel, and having means for engaging the shoe to partake of corresponding movement of the latter, and means operable by simple oscillatory movement of said follower to impart a compound movement to said heel-positioning member.
3. A heel-shaping machine comprising a cutter for trimming the periphery of an attached heel, a member arranged to engage the heel to position it relatively to the cutter, a follower formed and arranged to embrace the shoe and to be moved thereby about an axis substantially parallel to the height of the heel, said follower being adjustable to accommodate shoes of different sizes, and means operable by said follower to shift said heel-positioning member.
4. A heel-shaping machine comprising a cutter for trimming the periphery of an attached heel, a toplift guard, a rand-crease guard spring-pressed in a direction toward said toplift guard and adapted to yield in the opposite direction, and means operable by the shoe to shift said toplift guard heightwise of the heel.
5. A heel-shaping machine comprising a cutter for trimming the periphery of an attached heel, a toplift guard, a rand-crease guard spring-pressed in a direction toward said toplift guard and adapted to yield in the opposite direction, a heel-rest arranged to engage the periphery of the heel to sustain the cutting stress of said cutter, and means operable by the shoe to shift said toplift guard heightwise of the heel and to shift said heel-rest widthwise of the heel.
6. A heel-shaping machine comprising a cutter for trimming the periphery of an attached heel, a movable toplift guard, a movable heel-rest, and mechanism operable by the shoe to shift said guard and said heel-rest heightwise of the heel.
7. A heel-shaping machine comprising a cutter for trimming the periphery of an attached heel, a movable toplift guard, a movable heel-rest, mechanism operable by the shoe to shift said guard and said heel-rest heightwise of the heel, and mechanism operable by the shoe to move said heel-rest widthwise of the heel.
8. A heel-shaping machine comprising a cutter for trimming the periphery of an attached heel, a carriage, mechanism operable by the shoe to shift said carriage heightwise of the heel, and a toplift guard and a heel-rest both carried by said carriage.
9. A heel-shaping machine comprising a cutter for trimming the periphery of an attached heel, a carriage, mechanism operable by the shoe to shift said carriage heightwise of the heel, a toplift guard and a heel-rest both carried by said carriage, and mechanism operable by the shoe to move said heel-rest relatively to said carriage.
10. A heel-shaping machine comprising a cutter for trimming the periphery of an attached heel, two movable heel-engaging members, and mechanism operable by the shoe to impart a simple shifting movement to one of said members and a compound shifting movement to the other.
11. A heel-shaping machine comprising a cutter for trimming the periphery of an attached heel, two movable heel-engaging members, mechanism operable by the shoe to impart a simple shifting movement to one of said members and a compound shifting movement to the other, and means arranged to regulate the direction of said simple movement and one component of said compound movement.
12. A heel-shaping machine comprising a cutter for trimming the periphery of an attached heel, a movable toplift guard, and mechanism operable by turning movement of the shoe in one direction to shift said toplift guard first in one direction and then in the opposite direction.
13. A heel-shaping machine comprising a cutter for trimming the periphery of an attached heel, a movable toplift guard, a movable heel-rest, and mechanism operable by turning movement of the shoe in one direction to shift said toplift guard in opposite directions and said heel-rest in one direction.
14. A heel-shaping machine comprising a cutter for trimming the periphery of an attached heel, a movable toplift guard, a movable rand-crease guard, a spring arranged to shift one of said guards toward the other, and means operable by the shoe to shift said other heightwise of the heel.
15. A heel-shaping machine comprising a cutter for trimming the periphery of an attached heel, a movable toplift guard, a movable heel-rest, mechanism operable by the shoe for shifting said members

collectively and for otherwise shifting one of them relatively to the other.

34. A heel-shaping machine comprising a cutter having a curved profile for trimming the periphery of an attached heel, a movable toplift guard having a lip to engage the periphery of the toplift, means operable by the shoe for moving said guard heightwise

of the heel to cover and uncover portions of said cutter, and means for guiding said guard so that the movements of said lip will parallel said profile.

In testimony whereof I have signed my name to this specification.

ALFRED B. FOWLER.
